F. S. McCULLOUGH

METHOD OF HEAT TREATING PORCELAIN

Filed March 21, 1925

INVENTOR
Frederick S. McCullough
BY
C. M. Clarke
ATTORNEY

UNITED STATES PATENT OFFICE.

FREDERICK S. McCULLOUGH, OF WILKINSBURG, PENNSYLVANIA.

METHOD OF HEAT TREATING PORCELAIN.

Application filed March 21, 1925. Serial No. 17,260.

To all whom it may concern:

Be it known that I, FREDERICK S. McCULLOUGH, a citizen of the United States, residing at Wilkinsburg, in the county of Allegheny and State of Pennsylvania, have invented certain new and useful Improvements in Methods of Heat Treating Porcelain, of which the following is a specification.

10 This invention relates to a method of firing or heat treating porcelain or similar earthen substances.

In certain electrical and other devices for scientific and commercial use, it is desirable to have a porcelain of extremely fine grade. The object of the present invention is to provide a method of heat treating or firing porcelain wherein the porcelain may be subjected to extremely high temperatures 20 in a vacuum, whereby a porcelain of very fine grade may be obtained, and a porcelain suitable for various purposes of a scientific nature can be produced.

The invention contemplates the firing of 25 the porcelain either in an evacuated vessel in which the porcelain is permanently mounted for use, or the heat treating of porcelain in a vessel from which it may be subsequently removed for use in various devices.

The invention may be readily understood by reference to the accompanying drawing illustrating diagrammatically the method which the present invention contemplates. 35 It will be understood that the invention is not restricted to the particular devices or apparatus shown, the drawing being merely for the purpose of illustration.

In the drawings:

40 Fig. 1 represents a vertical section through a vessel having a porcelain rod therein, and having elements associated therewith for effecting the process;

45 Fig. 2 represents a transverse section on line II—II of Fig. 1; and

Fig. 3 is a view similar to Fig. 1, showing a slightly modified arrangement.

Referring to Figs. 1 and 2, 5 designates a 50 suitable envelope which may have a permanent or removable stopper 6 in its base, or at any other suitable point, and which may have an outlet 7 at one end thereof that may be connected to an exhaust line, whereby extremely high vacuum may be produced within the vessel. Mounted within the vessel by 55 means of a suitable stem or supporting wire

8 that may be carried by the plug 6, is a metallic sleeve 9, into which is set or fitted a raw or partially fired porcelain or other earthen rod 10. Surrounding the vessel 5 60 is a coil 11 which may be connected with a high frequency alternating circuit designated α .

In practicing the invention, the porcelain rod is mounted inside the metal sleeve 9, as above described, and a current of high frequency is then passed through the external coil 11. The alternating field produced by the coil will serve to induce eddy currents in the metal sleeve 9, heating the sleeve to an extremely high temperature. This heat will, of course, be transmitted both by conduction and radiation to the porcelain rod 10, serving to fire the porcelain. During the firing operation, an extremely high vacuum 70 may be maintained within the vessel. If the porcelain is to remain in the vessel permanently, the outlet 7 may be sealed off upon completion of the firing operation.

In the arrangement shown in Fig. 3, the 75 method is substantially similar. In this figure, 12 designates the envelope, 13 the plug at the base of the envelope, 14 is the connection to the exhaust line, and 15 is the supporting stem in the base or plug which carries the metal cylinder 16. The porcelain rod 17 is inserted in the tube 16.

Surrounding the tube 16 and spaced therefrom, there may be a second tube 18 of 80 larger diameter. This second tube may be carried on a suitable support, such as 19. Surrounding the envelope is the coil 20 connected in the high frequency circuit including a source α' .

With the arrangement shown in Fig. 3, the 85 external cylinder 18 will be heated to an extremely high temperature by the introduction of eddy currents therein when the external coil is energized. Heat from this plate or tube will be radiated and concentrated on the inner tube 16, by means of which the porcelain rod 17 will be highly heated. During the practice of this method, the high vacuum may also be maintained in the vessel.

Various other structures and devices may 90 be utilized for practicing the method within the contemplation of the present invention.

I claim as my invention:

1. The method of firing porcelain which 95 consists in encasing the porcelain by a metal shell, mounting the shell in a vessel, main-

taining a vacuum in the vessel, and heating the metal shell while the same is maintained in a vacuum.

2. The method of firing porcelain which 5 consists in placing the porcelain within a metal receptacle inside of an evacuated vessel, and maintaining an alternating current field about the vessel to heat said metal receptacle.

10 3. The method of heat treating porcelain which consists in surrounding a body of porcelain with a metal casing, mounting said casing within a vessel, connecting the vessel with an exhaust line exhausting the vessel, and heating the metal casing and porcelain while the vessel is connected with the exhaust line.

15 4. The method of heat treating porcelain which consists in placing a porcelain rod in-

side a metal cylinder, mounting said cylinder and rod within a vessel, connecting said vessel to an exhausting pump exhausting the vessel, and heating the cylinder and the porcelain by means of an external coil.

20 5. The method of heat treating porcelain which consists in forming a porcelain rod, enclosing the porcelain rod in a metallic cylinder, mounting such cylinder and rod inside a vessel, surrounding the cylinder and rod with a second cylinder, connecting said vessel with an exhaust pump exhausting the vessel, and maintaining an alternating current field within the tube to heat the metal cylinders and the porcelain within the tube.

25 30 35 In testimony whereof I hereunto affix my signature.

FREDERICK S. McCULLOUGH.
